UNITED STATES PATENT OFFICE.

JOHN F. O'CONNOR, OF CHICAGO, ILLINOIS, ASSIGNOR TO WILLIAM H. MINER, OF CHICAGO, ILLINOIS.

SIDE BEARING FOR RAILWAY-CARS.

Specification of Letters Patent. Patented June 17, 1913.

1,065,671.

Application filed April 25, 1912. Serial No. 893,022.

To all whom it may concern:

Be it known that I, JOHN F. O'CONNOR, a citizen of the United States, residing at Chicago, in the county of Cook and State 5 of Illinois, have invented a certain new and useful Improvement in Side Bearings for Railway-Cars, of which the following is a full, clear, concise, and exact description, reference being had to the accompanying 10 drawings, forming a part of this specification.

My invention relates to improvements in side bearings for railway cars.

One object of my invention is to provide 15 side bearings strong, simple, efficient and of durable construction.

A further object is to provide side bearings which will permit an increase, over the present railroad practice, of the clearance 20 space between the upper and lower bolster bearing plates under excessive oscillation of the bolsters.

A further object is to provide side bearings which in their action will compensate 25 for the wear of the bolster center plates.

A further object is to provide side bearings having a resilient member capable of absorbing shock and reducing the concussion 30 between the upper and lower bolsters due to the tipping of the bolsters under load, and the oscillations of the car body.

My invention consists in the means that I employ to practically accomplish these objects, as herein shown and described, and 35 more particularly pointed out in the claims.

In the accompanying drawings forming a part of this specification Figure 1 is an end view of the upper and lower bolsters of a railroad car provided with side bearings 40 embodying my invention. Fig. 2 is an elevation of side bearings shown in place between the upper and lower bolsters. Fig. 3 is an enlarged end view showing details 45 of both upper and lower bearings. Fig. 4 is a bottom plan of the resilient bearing. Fig. 5 is a plan view of one end of the resilient bearing plate.

In the drawings 6 represents the body bolster of a car, 7 the truck bolster, 8 the 50 lower side bearing base casting secured to the truck bolster, 9 the upper side bearing base casting secured to the body bolster, 10 an anti-friction roller, 11 a supplemental rocker or cradle interposed between the anti-friction roller and the lower base casting. 55

The lower base casting 8 is secured to the truck bolster by bolts or rivets 12, which pass through its base flange 13, and is provided with integral flanges or lugs 14 to receive between them the supplemental rocker 60 or adjustable cradle 11.

The anti-friction roller 10 may be of any suitable form—that illustrated in the drawings being cylindrical, and provided with trunnions 16 at each end. The trunnions 65 16 are provided with suitable bearings 17 rigidly secured in adjustable cradle 11.

The upper base casting 9 is secured to the body bolster 6 by bolts or rivets 18, 19, which pass through its base flange 19. The upper 70 base casting is provided with suitable means for securing at either end the resilient bearing plate 20. I prefer to secure the end of the bearing plate 20 by providing the base casting 9 with the depending flanges 21, 21 75 forming the slots 22, 22 into which the bearing plate 20 may be slipped. The flanges 21, 21 are preferably notched, as indicated at the points 23, 23, to permit the insertion of the rivets 24, 24, which are 80 passed through the perforations 25, 25 in the base casting 9, and engage the resilient bearing plate 20 at the notches 26, 26 provided at either end of the bearing plate 20, as shown in Fig. 5. 85

The spring or bearing plate 20 furnishes an extended tread face 28 with which the anti-friction roller 10 directly contacts. The bearing plate 20 is made of resilient metal, preferably flat spring steel of suitable thickness and strength to yieldingly resist pressure transmitted through the anti-friction roller. The face 27 of the base casting 9 opposite the anti-friction roller 10 is suitably cut away or hollowed out between its ends to furnish a bearing at each end for the spring or resilient bearing plate 20, and at the same time to permit the flexing of the spring 20 toward the face 27. I prefer to accomplish this by making the 100 face 27 of the base casting 9 curved between its ends, as shown in Fig. 3, thus permitting the spring or resilient bearing plate 20 to rest throughout its length against the face 27 upon its extreme flexing movement. The 105 notches 26 in the plate 20 provide a suitable loose engagement with the rivets 24, 24 to permit the movement of the resilient bearing plate 20. Also the bearing plate 20 by reason of its flexing under load tends 110

to curve about the anti-friction roller, thus enlarging the area of contact between the anti-friction roller and bearing plate over the area of contact provided by a bearing plate, which at all times presents a tread surface in a straight plane, and thus also tending to right the car trucks in their relation to the car body.

I claim:—

10. 1. In a side bearing for railway cars, in combination an upper and a lower base casting, an anti-friction roller secured to one of said castings, a flat spring secured to the other of said castings providing a tread member for said roller, said last mentioned casting being provided with a hollowed out face adapted for the flexure of said spring therein on pressure of the roller thereon.
2. In a side bearing for railway cars, the combination of an upper and a lower base casting with a flat plate of resilient metal interposed between them, and an anti-friction roller secured to one of said castings, the other base casting being provided with a curved surface within which the spring may bend under pressure.
3. In a side bearing for railway cars, the

combination of an upper and a lower base casting with a flat plate of resilient metal interposed between the base castings, and an anti-friction roller secured to one of said castings, the other base casting being provided with seats for either end of the said spring, and a space between said seats within which the said spring may bend.

4. In a side bearing for railway cars, the combination of an upper and a lower base casting with a flat plate of resilient metal interposed between them, and an anti-friction roller secured to one of said castings, the other base casting being provided with seats for either end of the said spring, and a space between said seats within which the said spring may bend, the said spring being held in position by flanges extending over said seats, each of said flanges being perforated to receive a rivet, and the said spring being notched at either end to engage said rivets.

JOHN F. O'CONNOR.
